UNITED STATES PATENT OFFICE

2,511,062

RAIL ANCHOR

Jacob Alvin Hyle, Detroit, Mich., and Robert Andrew Thomann, Clayton, Mo.

Application September 25, 1945, Serial No. 618,516

1 Claim. (Cl. 238—327)

1

This invention relates to rail anchors and is an improvement over the anchor embodied in our pending application, Ser. No. 483,800 filed April 20, 1943 for rail anchors, which application has become abandoned.

An object of this invention is to provide an improved rail anchor that can be constructed from bar metal.

Another object of this invention is to provide an improved anchor which is so constructed that it will provide an increased bearing surface against the cross tie.

A further object of this invention is to provide an anchor of this type wherein the jaws and the body of the anchor are held out of engagement with the tie plate.

A further object of this invention is to provide an anchor of this type which can be used on either side of the track rails which when in applied position will provide a more efficient anchor so that a smaller number of these anchors may be used per rail length.

To the foregoing objects and others which may hereinafter more fully appear, the invention consists of the novel construction, combination and arrangement of parts as will be more specifically referred to and illustrated in the accompanying drawings but it is to be understood that changes, variations and modifications may be resorted to which fall within the scope of the invention, as claimed.

In the drawings:

Figure 1 is a detail side elevation of a rail anchor constructed according to an embodiment of this invention mounted on a rail which is shown in section.

Figure 2 is a top plan of the anchor.

Figure 3 is an end elevation of the anchor.

Figure 4 is a sectional view, taken on the line 4—4 of Figure 3.

Figure 5 is a plan view of the blank from which the anchor is formed.

Figure 6 is a detail side elevation of the blank from which the anchor is formed.

Figure 7 is a detail end elevation of the blank showing in dotted lines the manner in which the flanges or wings are bent downwardly to form the anchor bodies.

Referring to the drawings the numeral 10 designates generally a rail of conventional construction which is provided with a pair of oppositely extending base flanges 11 and 12. The rail 10 is seated on a tie plate 13, which engages on the upper side of a cross tie 14.

A rail anchor, generally designated as 15, is

2

clamped on the flanges 12 and 13 at one side of the cross tie 14. The anchor 15 comprises an elongated bar 16 which is formed with a reduced thickness central portion 17 formed by cutting out a portion from the upper side of the bar thereby forming a resilient intermediate portion 18.

The bar 16 has an upwardly extending jaw 19 which is engageable with the outer edge of the base flange 12 and the opposite end of the bar 16 is formed with a substantially C-shaped jaw 20 engageable over the base flange 11. The inner side of the jaw 20 is bevelled, as indicated at 21, so as to provide for the firm engagement of a substantial portion of the jaw 20 with the upper surface of the inclined flange 11. The bar 16 has extending downwardly therefrom a pair of laterally offset anchoring bodies or plates 22 and 23. The inner surfaces 24 and 25 of the anchoring members 22 or plates 22 and 23 are formed as a section of a parabola and the upper horizontal edges 26 and 27 of the anchoring members 22 and 23 extend laterally from the opposite sides of the bar 16 and provide a means for holding the bar 16 from contact with the adjacent edge or end of the tie plate 13, as shown more clearly in Figure 3.

The anchoring members 22 and 23, as shown in Figures 1 and 2, are formed with cutouts 28 and 29 adjacent the reduced thickness portion 18 of the bars 16 so that the resilient intermediate portion 18 may flex independent of the anchoring members 22 and 23. The C-shaped jaw 20 is formed with a groove 30 in its outer side thereby forming a pair of parallel ribs or reinforcing members 31 and 32 on the opposite sides of the jaw at the outer edge portion thereof.

In practice the groove 30 extends downwardly and then through the lower side of the bar 16, as this groove is formed initially in the rolling of the bar from which the anchor is formed.

Referring now to Figures 5, 6 and 7, there is disclosed a method by which the anchor hereinbefore described is formed. An elongated bar 33 is formed with laterally extending tapered flanges 34 and 35 which extend from the lengthwise edges thereof and the lower side of the bar 33 is formed with a V-shaped channel 36.

The bar 33 and the flanges 34 and 35 are heated to the desired degree and the bar is then passed through a die which removes the flanged portions 37 and 38 leaving an extending bar portion 39. The extended bar portion 39 is subsequently bent upwardly into C-shape so as to form a jaw 20. The opposite ends of the flanges 34 and 35 are then cut off as indicated at 40 and

41 leaving a relatively short extension 42 which is bent upwardly in the manner shown in Figure 1 to form a jaw 19. The flanges 34 and 35 are then cut out as indicated at 43, and 44, on opposite lengthwise edges of the bar 33 so as to form the cutouts 28 and 29 and then the upper side of the bar 33 is cut out along the dotted line 45, so as to form the reduced thickness resilient intermediate portion 18.

The remaining portions of the flanges 34 and 35 are then bent downwardly in the form as shown in dotted lines in Figure 7 so as to form the depending anchoring members 22 and 23.

In applying the anchor the jaw 19 is initially disposed beneath the flanges 11 and 12, with the C-shaped jaw 20 loosely engaging the flange 11. The jaw 20 is then struck with a hammer or other tool until the jaw 19 snaps upwardly into clamping engagement with the outer edge of the base flange 12. The clamp is disposed on either rail of a pair and by providing the pair of anchoring members 22 and 23 the anchor may be used on either right or left hand rail or on either side of either rail so that it will not be necessary to provide two sets of anchors for a rail.

The anchoring member 22, as shown in Figure 3, is adapted to substantially abut against the adjacent side of the tie 14 and in this position the bar 16 is spaced from the adjacent edge or side of the tie plate 13 so that the latter cannot contact with the anchor. As the tie plate 13 does not contact any portion of the anchor, the anchoring members 22 and 23 will gradually wear against the adjacent side of the tie 14 depending on which anchoring member is confronting the tie as the cars pass over the rails and produce a wave motion in the rails.

It is well known that when the rail anchor engages against the tie plate both the tie plate and the tie will shift in the roadbed requiring replacement of the tie to its original position which also includes retamping and forming of the roadbed.

We claim:

A rail anchor comprising an elongated bar having an elongated cutout between the ends thereof extending downwardly from the upper side thereof 5 of forming a reduced thickness intermediate portion having a degree of resiliency greater than the outer portions of said bar, a C-shaped clamping jaw extending upwardly from one end of said bar, a second jaw at the opposite end of said bar, and a pair of laterally offset plates extending from the lower side of said bar, each of said plates having an elongated cutout extending downwardly from said bar and disposed directly beneath the reduced portion of said bar, said latter 15 named cutouts forming reduced intermediate portions in the plates having a substantial degree of resiliency whereby said plates may flex with said bar during the mounting of the anchor on a rail.

20 JACOB ALVIN HYLE.
ROBERT ANDREW THOMANN.
